his Attorney

UNITED STATES PATENT OFFICE

RUSSELL SMITH HARRIS, OF ST. MARY'S, ONTARIO, CANADA

PENCIL SHARPENER

Application filed May 29, 1930. Serial No. 456,979.

This present invention relates to certain new and useful improvements in a pencil sharpener.

The primary object of the invention resides in the provision of a pencil sharpener which will efficiently serve the purpose for which it is intended while rotating the pencil.

Another object of the invention resides in the provision of a pencil sharpener of the character stated which may be readily held stationary and a pencil rotated therein to sharpen the pencil.

A further object of the invention resides in the provision of a pencil sharpener of the character stated which will serve to firmly hold the pencil and guide the same as it is sharpened.

A still further object of the invention resides in the provision of a pencil sharpener of the character stated which will hold the pencil by the same means operating to rotate the pencil against the sharpening drums for sharpening the pencil.

A still further object of the invention resides in the provision of a pencil sharpener of the character stated having improved pencil holding and rotating means co-operating with a simple arrangement of sharpening drums.

The invention has for a still further object the provision of a pencil sharpener of the character stated which is of improved, simplified and compact construction, composed of the minimum number of parts and highly efficient in operation.

The invention has for a still further object the provision of a pencil sharpener of the character stated which may be manufactured at small cost and retailed at a popular price with good profit, thus providing a commercially attractive proposition.

To the accomplishment of these and related objects as shall become apparent as the description proceeds, my invention resides in the construction, combination and arrangement of parts as shall be hereinafter more fully described, illustrated in the accompanying drawings and pointed out in the claims hereunto appended.

The invention will be best understood and

can be more clearly described when reference is had to the drawings forming a part of this disclosure, wherein like characters indicate like parts throughout the several views.

In the drawings:—

Figure 1 is a longitudinal horizontal section through the pencil sharpener with one section of the casing removed;

Figure 2 is an end elevation, showing the clamping means for the pencil; and

Figure 3 is a fragmentary side elevation, at right angles to Figure 2.

Referring more in detail to the drawings, it is to be noted that the casing 6 which is of elongated cylindrical form is constructed in sections or in halves connected by appropriate connecting members extended through registering outwardly directed ears 7 at the longitudinal edges of the sections or halves. The casing 6 has a flat rear end 8 and an outwardly curved concavo convex forward end 9 with a central opening 10 having an outwardly directed flange or neck 11 around the wall thereof. A plurality of pencil sharpening drums 12 having spiral blades 13 thereon are rotatably mounted in the casing 6 in such a manner as to diverge forwardly. The rear ends 14 of the central longitudinal shafts for the drums 13 are rotatable in bearings 15 carried by the end wall 8 of the casing 6, while the forward ends 16 of said shafts are extended through the forward end wall 9 of the casing 6 and rotatable therein. Pinions 17 are carried on the outer extremities of the forward shaft ends 16 for meshing engagement with and driving by the bevel internal gearing 18 in the inner face of the annular flange 19 of the disc 20. This disc 20 has a central opening with a collar 21 extended from the inner or rear face of the disc 20, around said opening of the latter and adapted for rotation in the neck 11. The collar 21 has a radially extended annular flange 22 at its inner end for engagement with the inner face of the forward end 9 of the casing 6 to prevent the collar 21 from moving outwardly in the sleeve 11 when the parts or sections of the casing 6 are assembled and secured together. Carried on the outer face of the disc 20 at diametrically opposite points,

are the pairs of ears 23. Within each pair of ears 23 is pivotally mounted the rear end of one link 24 of a toggle arm, the other link 25 of which is pivotally connected with the forward end of the first mentioned link 24 and has, in turn, its forward end pivotally mounted on an outwardly directed extremity 26 of a lower substantially V-shape pencil clamping member 27. Each outer link 25 is also braced by a bottom brace plate 28 located therebeneath and having its forward end mounted on the pivot member for the forward end of the link 25 while the upwardly offset remaining end of the brace plate 28 is fastened to the under face of the link 25. A complementary inverted V-shape pencil clamping member 29 is supported above the V-shape pencil clamping member 27, with its outwardly directed extremities 30 riding on the upstanding posts 31 and 32 carried by the said outwardly directed extremities 26 of the clamping member 27 and on which upstanding posts 31 and 32 are mounted the outer links 25 of the toggle arms, as previously mentioned. The upstanding post 32 has its upper extremity 33 turned at an angle to support thereon the locking cam 34 having a radially extended handle 35, so that the cam 34 may be readily turned on the upper extremity 33 of the upstanding post 32 to operate on the upper face of the outwardly directed extremity 30 of the pencil clamping member 29 through which the upstanding post 32 is engaged. To counteract the effect of the cam 34 and resiliently retain the V-shape pencil clamping member 29, in its uppermost position, the expansion spring 36 is provided around the upstanding post 32, between the outwardly directed extremities 26 and 30 of the pencil clamping members 27 and 29, respectively. It is thus apparent that the pencil clamping members 27 and 29 will be caused to thoroughly co-operate in firmly clamping therebetween the pencil 37 to be sharpened, with the end 38 thereof engaged between the pencil sharpening drums 13, during operation of the pencil sharpener so that the pencil end 38 may be thoroughly sharpened and pointed by the pencil sharpening drums 13.

As the construction of the device has thus been described in detail, brief reference is now had to its use and modus operandi: To sharpen a pencil with this pencil sharpener, it is simply necessary to adjust the pencil 37 through the space between the pencil clamping members 27 and 29 and through the collar 21 to bring the end of the pencil into engagement with the co-operating pencil sharpening drums 13. Then close the pencil clamping members 27 and 29 firmly upon the pencil 37 by proper adjustment of the cam 34. The device is then ready for operation by turning or rotating the pencil 37 and forcing lightly inwardly on the same,

with the casing 6 held stationary by one hand or by securing the casing 6 on a stationary support. The toggle arm connections between the pencil clamping members 27 and 29 and the disc 20 permit a constant inward movement of the pencil 37 as the same is rotated and which rotation also compels an opposite rotation of the pencil sharpening drums 13, through the medium of the internal gear 18 and the pinions 17. Thus, the end 38 of the pencil 37 is evenly operated upon to quickly and efficiently sharpen the point thereof.

From the foregoing description taken in connection with the accompanying drawings, it will be manifest that a pencil sharpener is provided that will fulfill all the necessary requirements of such a device but as many changes could be made in the above description and many apparently widely different embodiments of my invention may be constructed within the scope of the appended claims without departing from the spirit or scope thereof, it is intended that all matters contained in the said accompanying specification and drawings, shall be interpreted as illustrative and not in a limited sense.

Having thus described my invention, what I claim as new and desire to secure by Letters Patent is:—

1. A pencil sharpener including a pair of rotatable pencil sharpening members; pencil operated rotating means for rotating said members; and pencil clamping means carried by the said pencil operated rotating means. 100
  2. A pencil sharpener including sharpening members; a pencil operated rotating means for rotating said members; a clamping means for a pencil; and toggle connections between said clamping means and the said rotating means for the sharpening members. 105
  3. A pencil sharpener including diverging pencil sharpening members; pencil operated rotating means for rotating said members; pencil clamping means; and toggle connections between said pencil clamping means and the said pencil operated rotating means for the pencil sharpening members. 110
  4. A pencil sharpener including a casing; pencil sharpening means operable within said casing; pencil operated rotating means for rotating said pencil sharpening means; pencil clamping means; and connections between said pencil clamping means and the said pencil operated rotating means. 115
  5. A pencil sharpener including a casing; pencil sharpening members operable within said casing; pencil operated rotating means for rotating said members; co-operating pencil clamping members; means to retain said pencil clamping members in operative engagement with a pencil positioned therebetween; and toggle-like connections between said pencil clamping members and the said 120
- 125
- 130

pencil operated rotating means to cause operation of the latter and allow feeding of the pencil end to the said pencil sharpening members as the pencil is rotated and pressed 5 inwardly.

In testimony whereof I hereunto affix my signature.

RUSSELL SMITH HARRIS. [l. s.]
